United States Patent Office

Des. 205,290
Patented July 19, 1966

205,290

NIGHT STAND

Bert J. Klein and Andre Bus, Altavista, and John B. Thorn, Lynchburg, Va., assignors to The Lane Company, Inc., Altavista, Va., a corporation of Virginia

Filed Apr. 19, 1965, Ser. No. 84,864

Term of patent 14 years

(Cl. D33—14)

Fig. 1.

Fig. 2.

The end of the article not shown is like the end shown and the back is conventionally plain.

We claim:

The ornamental design for a night stand, as shown and described.
